GARMENT PRESSING MACHINE

Thomas Yosyk, Ridgewood, N. Y.

Application April 18, 1934, Serial No. 721,191

5 Claims. (Cl. 68—9)

My invention relates to improvements in garment pressing machines of the type embodying a fixed pressing element or buck on which garments or fabrics to be pressed are arranged, and a movable pressing element supported by a lever and swingable against and away from the fixed element.

In garment pressing machines of the above general type, there have been several provisions and suggestions for means to adjust the angularity or position of the movable pressing element or head with respect to the fixed element, to accommodate fabrics and garments of various and/or varying thicknesses. Such arrangements necessitate a change in the adjustment each time garments or fabrics of different thicknesses are placed on the fixed pressing element or buck before the movable pressing element or head is brought down into the pressing position.

I have discovered a relatively simple and highly effective means for constructing a garment pressing machine, so that it is not necessary to make an adjustment of the angularity of the movable pressing element each time garments or fabrics of different thicknesses are to be pressed, and this discovery forms part of the subject matter of the present application.

As will be hereinafter more clearly understood, the present invention resides principally in the provision of a connection between the toggle at the rear of the pressing machine and the lever which carries the movable pressing element, wherein provision is made for automatic adjustment of the angularity of the head with respect to garments or fabrics of various or varying thicknesses upon closing the press, and for increased pressure.

A more specific feature of the invention includes the provision of such automatic compensating connection between the rear toggle and lever carrying the movable pressing element at a point immediately beneath and in line with the usual counter-balancing weight on the rear of said lever.

Another specific feature of the invention resides in the provision of a system of toggles so constructed and arranged as to operate not only with facility but to have a compact folding movement when the toggles are broken, resulting in economizing in space and amount of material without sacrificing ease of movement or pressure.

All of the objects and advantages of the invention will become more apparent and will be pointed out during the course of the following detailed description of the accompanying drawings, in which

Fig. 1 is a side elevation with parts in section; Fig. 1a is a fragmentary more or less diagrammatic view of certain parts shown in Fig. 1 under conditions hereinafter explained;

Fig. 2 is a view similar to Fig. 1 showing the press in open position;

Fig. 3 is a top plan view of the press in closed position;

Fig. 4 is a rear elevation of the press in the same position; and

Fig. 5 is a sectional view taken on the line 5—5 of Fig. 2.

In the drawings the numeral 6 designates the frame of the machine on which is a table 7 to support garments to be pressed and above which is the fixed pressing element or buck 8. The lever 9 carrying the movable pressing element or head 10, is pivotally mounted at 11 on the upper rear portion of the frame. An actuating or pedal lever 12 is fulcrumed to the frame at 13, and as shown best in Fig. 5, the lever 12 is forked providing two arms which are pivoted on the pin or shaft 13. A bracket 15 is secured to the front of the frame as by bolts 16 and extends rearwardly, being provided with a depending ear 16, to which is pivotally connected at 18 to another member 19, and forming therewith a toggle. The shorter arm of the member 17 is pivotally connected at 20 to an adjustable link 21 also connected to the pedal lever 12 at 22. A bumper or stop 23 is mounted in the bracket 15 to engage an abutment 24 on the long arm of the member 17 when the toggle 17—19 is straightened as shown in Fig. 1.

The member 19 is pivotally connected at 25 to the link 26 of the rear toggle which is also pivotally mounted on the shaft 13 between the arms 14 of the lever 12, and is connected at 27 to a relatively short adjustable link 28. A spring 29 is connected at 30 to the link 26 of the rear toggle and is also connected to the shaft 31 on which the member 17 is pivoted, said spring normally tending to break the rear toggle and assist in returning the parts from the position of Fig. 1 to the position of Fig. 2.

I call attention to the fact that the toggle 26—28 breaks toward the front of the machine, and the toggle 17—19 breaks toward the base of the machine, and since the arm of the member 17, which is connected to the link 19 is relatively long, the pivot 18 at open position of the press is disposed between the arms 14 of the lever 12.

The compensating connection between the toggle mechanism and the head lever 9 which, as previously mentioned, permits pressing garments and fabrics of varying or various thicknesses without adjusting the angularity of the head lever before each pressing operation is shown best in Figs. 1 and 2. The upper end of the link 28 is forked as indicated by the numeral 32 in Fig. 4, and between the arms 32 is disposed a depending web 33 of a plate or lever 34 about to be described, and a pin 33' is disposed through the

forked arms 32 and the ribs 33 pivotally connecting the parts.

The lever 34 has formed on its upper surface an upstanding lug or ear 35, and on one side thereof adjacent the rear a recess 36. At a corresponding point adjacent the front of the lever is a screw threaded opening closed by a plug 37. The rear portion of the head lever 9 has a chamber 38 formed in the upper surface of its rear end adapted to receive a counterweight 39, and closed by a plate 40 held in place by a bolt and nut 41. Directly beneath the chamber 38 the rear end of the head lever is provided with a pair of recesses 42 and 43. Between the recesses are depending lugs or eyes 44 between which is disposed the lug or ear 35, so that a pin 45 may pivotally connect the head lever and the lever 34. Seated in the recess 43 is one end of the coil spring 46, the other end of which bears against the plug 37. A similar spring 47 is mounted in the recesses 42 and 36. The springs are of appreciable thickness and strength and are compressed between the head lever and the lever 34, but the springs are not completely compressed. The plug 37 is provided so as to facilitate assembly and repair, for when the plug is removed the spring 46 may be easily removed whereupon the lever will rock on the pivot 45 to permit removal of the spring 47.

In operation when the pedal lever 12 is depressed from the position of Fig. 2 it exerts a pull through link 21 on the short arm of link 17, rocking the latter on the pivot 31 and consequently straightening the toggle 17-19 which results in straightening the toggle 26-28 against the actuation of spring 29. During the straightening of toggle 26-28 pressure is exerted at pivot 33' below spring 47 on the lever 34 and this pressure is transmitted to the extreme rear end of the head lever 9, causing the same to rock on pivot 11 and thereby closing the press. Due to the fact that the lever 34 is pivoted intermediate its ends to the head lever, it is free to rock within limits permitted by the springs 46-47, and the same being true of the head lever 9, the latter may automatically adjust its angularity with respect to the buck and the goods thereon. An illustration is given in Fig. 1a wherein the spring 47 is compressed more than spring 46. In fact the latter is shown expanded beyond its normal position, due to the compression of the spring 47, and, I find, this expansion of the spring 46 increases the pressure by rocking lever 34 on its pivot 45. I have found in actual practice that the machine may be used and the toggles completely straightened with goods ranging from the average thickness of a garment to goods at least an inch or more thick.

I claim:

1. In a garment pressing machine having a pair of cooperating pressing elements one of which is movable toward and away from the other, a lever supporting the movable element, a main toggle comprising upper and lower links, means to straighten said toggle, a second lever located substantially parallel to the longitudinal axis of the first lever and connected adjacent one end to the upper link of the toggle and pivotally connected intermediate its ends to said first lever, a spring between said levers substantially in alignment with said connection between the upper link and second lever and on one side of

the connection between said levers, and a second spring between said levers on the other side of said connection between said levers, said connections and springs affording relative movement between said levers to afford automatic adjustment of the movable element with respect to the fixed element according to the thickness of materials therebetween when said toggle is straightened to close the press. 5

2. In a garment pressing machine having a 10 pair of cooperating pressing elements one of which is movable toward and away from the other, a lever supporting the movable element, a main toggle comprising upper and lower links, means to straighten said toggle, a second lever 15 connected adjacent one end to the upper link of the toggle and pivotally connected intermediate its ends to said first lever and disposed beneath the rear end of said first lever substantially parallel thereto, a coil spring partially compressed 20 between said levers directly above said connection between the upper link and second lever, a second coil spring partially compressed between said levers on the other side of said connection between the levers, said connections and springs 25 affording relative movement between said levers to automatically adjust the movable element with respect to the fixed element according to the thickness of materials therebetween when said toggle is straightened to close the press. 30

3. In a garment pressing machine having a pair of cooperating pressing elements one of which is movable toward and away from the other, a lever supporting the movable element and having a counterweight at its rear end, a 35 main toggle comprising upper and lower links, means to straighten said toggle, a second lever connected to the upper link and pivotally connected intermediate its ends to the rear end of said first lever beneath said counterweight, a coil 40 spring partially compressed between said levers directly above said connection between the upper link and second lever, a second coil spring partially compressed between said levers on the other side of said connection between the levers, 45 said connections and springs affording relative movement between said levers to automatically adjust the movable element with respect to the fixed element according to the thickness of materials therebetween when said toggle is straightened to close the press. 50

4. In a garment pressing machine having a pair of cooperating pressing elements one of which is movable toward and away from the other, a lever supporting the movable element, a 55 second lever pivotally connected intermediate its ends to the rear portion of said first lever and arranged substantially parallel thereto, springs on opposite sides of said pivotal connection resiliently urging said levers apart but permitting relative rocking movement therebetween, a toggle comprising upper and lower links having the upper link pivotally connected to said second lever at one side of said pivot and substantially directly beneath one of said springs, and means 60 to straighten said toggle to close the press. 65

5. The structure of claim 4 wherein said second lever has a removable plug beneath one of the springs to permit removal of the springs without disconnecting said levers. 70
